UNITED STATES PATENT OFFICE.

RAY R. SIMPSON AND JOSEPH S. WILMOTH, OF DALLAS, TEXAS.

COMBINED ENVELOP, SHIPPING-TAG, AND INDEX-CARD.

1,157,432.

Specification of Letters Patent.

Patented Oct. 19, 1915.

Application filed March 5, 1914. Serial No. 822,616.

To all whom it may concern:

Be it known that we, RAY R. SIMPSON and JOSEPH S. WILMOTH, citizens of the United States, residing at Dallas, in the county of Dallas and State of Texas, have invented certain new and useful Improvements in Combined Envelops, Shipping-Tags, and Index-Cards, of which the following is a specification.

10 Our invention relates to a new and useful combined envelop, shipping tag and index card, which is particularly intended for the use of persons whose business involves the shipment of goods in containers which are 15 to be returned to the shipper.

It is the object of our invention to form from a single sheet of card board or paper, a card containing data identifying the shipment, which previous to the shipment will 20 be torn off by the shipper for his records, and an envelop and tag which will be attached to the container in which certain goods are shipped, the tag carrying the address of the consignee, and the envelop containing 25 the invoice, the invoice thus being transmitted to the consignee without expenditure for postage.

Another object is to provide two cards or checks attached to the envelop portion and 30 bearing similar designations and arranged to be detached from said portion, so that one may be retained at the shipping office and the other fastened to the container. By this arrangement a record of the shipping and 35 location of the retainer may be kept and upon return of the container the record may be so indorsed.

It is a further object of our invention to 40 provide a device of the character described, that will be strong, durable, simple and efficient and comparatively easy to construct.

With these objects in view, our invention 45 has relation to certain novel features of the construction, and use, an example of which is described in the following specification and is illustrated in the accompanying drawing, wherein:

Figure 1 is a rear view of the invention. Fig. 2 is a front view of the same. Fig. 3 50 is a development of the same. Fig. 4 is a transverse sectional view, taken upon the line *a—b* of Fig. 1.

Referring now more particularly to the drawing, wherein like reference characters 55 designate similar parts in all the figures, the

letters A, B, and C respectively designate an envelop, shipping tag and index card, which comprise our invention and are produced from a single sheet of cardboard or paper having the form illustrated in Fig. 3. 60 By reference to Fig. 3 it is seen that the members B and C project oppositely and integrally from the side of the sheet of which our invention is to be formed, the portion of the sheet lying between the members B 65 and C serving to form the front of an envelop, when a portion of the sheet projecting below said lateral members is turned over upon the central portion to form the back of 70 the envelop. That portion of the sheet 75 which lies above a line extended between the upper edges of the members B and C forms the flap of the envelop when turned down as shown in Fig. 1. At the juncture of each member B and C with the correlated member A, a line of perforations 1 is formed to facilitate the tearing apart of the three members.

The edge 3 of the back which comes beneath the flap 4 when the envelop is completed will preferably be of an arcuate shape to facilitate the introduction of any paper into the envelop. The back of the envelop will preferably be slit as indicated at 5 to receive an apex of the envelop flap, a slight hook 6 being preferably formed upon said flap to engage beneath one end of said slit to retain the flap in the slit. Some suitable adhesive such as is indicated by the numeral 2 will be employed to secure the lateral edges of the back of the envelop to the front thereof. It is preferred to aperture the two members B and C as is respectively indicated by the numerals 7 and 8 to facilitate attaching the former member by 90 a cord or wire to a container, and mounting the latter member upon a wire card filing member.

As is clearly shown in Fig. 2, the front of the envelop will contain the address of the consignee together with the words "Invoice enclosed". The shipping tag B and the index card C will contain duplicate printed forms to receive the number of the shipment, the name of the consignee, the time or date of the shipment, and the amount of 100 goods shipped.

In using our invention, before sending off any shipment of goods in a container, the shipper will fill in the data which the 110

members A B and C are arranged to carry, and he will then tear off the index card C and will keep it in his records. The container will be shipped with the integral 5 parts A and B secured to it. When the consignee receives the shipment, he will tear off the part A in which he will find his invoice. Thus the shipper will avoid the expenditure of time and postage incidental to 10 mailing out his invoices. The tag B will remain attached to the container and will not be removed therefrom until the container is returned to the shipper, who upon receipt of the container will check the same 15 off in his index cards. The index cards held by the shipper will constitute an accurate record of all the containers which have been sent out, and hence he need suffer no loss through the neglect of any consignee to return 20 a container.

While our invention is particularly adapted for the use of a dairy to insure the return of the milk cans, it is to be understood that the invention may be used for any ship- 25 per employing containers, the return of which is necessary.

The invention is presented as including all such changes and modifications as properly come within the scope of the following 30 claims:

What we claim is:

1. In a device of the character described, the combination with an envelop having its lateral edges pasted together, of a shipping tag, and an index card integrally connected 35 with the envelop at the lateral pasted edges thereof.
2. In a device of the character described, an envelop having its front and back portions integral, the lateral edges of said portions being pasted together, in combination with a shipping tag detachably secured to said envelop and projecting beyond a lateral pasted edge thereof. 40
3. In a device of the character described, 45 the combination with an envelop having its front and back portions integral, the lateral edges of said portions being pasted together, of a shipping tag and an index card integrally projecting from opposite lateral 50 edges of the front member of the envelop.

In testimony whereof we have signed our names to this specification in the presence of two subscribing witnesses.

RAY R. SIMPSON.
JOSEPH S. WILMOTH.
